Primary Examiner — Karen E Eldridge Powers(74) *Attorney, Agent, or Firm* — Kirk A. Buhler; Buhler & Associates(57) **CLAIM**

The ornamental design for a nursing scarf, as shown and described.

DESCRIPTION

FIG. 1 is a front perspective view of a nursing scarf showing my new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof;

FIG. 7 is a bottom plan view thereof;

FIG. 8 is a front perspective view of the nursing scarf shown in an environment of use thereof;

FIG. 9 is a front perspective view of the nursing scarf shown collected in an environment of use thereof;

FIG. 10 is a front perspective view of the nursing scarf shown in another environment of use thereof; and,

FIG. 11 is a rear perspective view of the nursing scarf shown in the environment of use of FIG. 10.

The broken lines in FIGS. 8-11 depict environmental subject matter of a person wearing the nursing scarf form no part of the claimed design.
